REFINING OF MINERAL OILS

Harold J. Moyer, Summit, N. J., assignor to Standard Oil Development Company, a corporation of Delaware

Application April 1, 1941, Serial No. 386,253

7 Claims. (Cl. 196—24)

The present invention is concerned with the refining of mineral oils. The invention is more particularly concerned with an improved process for producing a petroleum oil product boiling in the heating oil and gas oil boiling ranges which has a relatively low sulfur concentration. In accordance with my process, the vapors removed from the catalytic cracking zone are contacted with a hydrocarbon substance, preferably with a petroleum residuum which is characterized by having the ability to remove the sulfur compounds therefrom.

It is known in the art to refine petroleum oils by various distillation, cracking, reforming, and related operations. It is also known to produce various heating oil products by subjecting petroleum oils boiling in the gas oil and reduced crude boiling ranges to temperature and pressure conditions adapted to produce cracking of the same. In these thermal cracking operations the resulting cracked petroleum oil products, particularly the lower boiling oils, contain appreciably less sulfur than is present in the stock from which they originated. On the other hand, when feed oils of a similar character are catalytically cracked for similar boiling range products, the sulphur content of the cracked products is not appreciably reduced. I have now discovered a process by which catalytically cracked products may be readily reduced in sulfur which comprises contacting the same in the vaporous phase with a particular petroleum oil fraction which preferably comprises a relatively high boiling tar fraction.

My process may be readily understood by reference to the drawings illustrating embodiments of the same. Figure 1 illustrates a modification of my invention describing the method of contacting, while Figure 2 illustrates a preferred adaptation in which the heating oil products are contacted with a tarry fraction segregated in the reforming of a lower boiling range fraction. Referring specifically to Figure 1, it is assumed for purposes of description that the feed oil comprises a petroleum oil boiling in the gas oil boiling range and that the catalyst comprises an acid treated clay. The feed oil is introduced into catalytic reaction zone 1 by means of feed line 2 along with catalyst which is introduced by means of line 3. Temperature and pressure conditions are adjusted in reaction zone 1 adapted to secure the desired conversion of the feed oil. The cracked products are withdrawn overhead from zone 1 by means of line 4 and passed into separation zone 5 wherein the catalyst is separated from the reaction vapors. It is assumed for the purpose of description that separation zone 5

comprises a cyclone separator or equivalent means. The spent catalyst is withdrawn from separation zone 5 by means of line 6, regenerated and recycled or disposed of in any manner desirable. The cracked products are withdrawn from the separation zone by means of line 7 and passed into zone 8 wherein the cracked products are treated with a relatively high boiling high molecular weight hydrocarbon substance which is introduced into zone 8 by means of line 9. It is assumed that the hydrocarbon substance comprises a petroleum oil tar which is at a sufficiently high temperature so that the tar is in the fluid state. The treated cracked products substantially free of sulfur are removed overhead from treating zone 8 by means of line 10 and further refined as desired. The tar fraction is withdrawn from treating zone 8 by means of line 11 and also handled as desired. This fraction is usually cooled and utilized as a heavy fuel oil.

A preferred adaptation of my invention which comprises removing sulfur from a heating oil product by treating the same with a tar product segregated from a low boiling fraction is illustrated in Figure 2. For the purpose of description, it is assumed that the feed oil comprises a crude oil. The feed oil is introduced into distillation zone 20 by means of feed line 21. Temperature and pressure conditions are adjusted in distillation zone 20 to segregate a fixed gas stream 30 which is removed overhead by means of line 22, a light naphtha stream which is removed by means of line 23, a heavy naphtha stream which is removed by means of line 24, a gas oil stream which is removed by means of line 25, and a crude bottom stream which is removed by means of line 46. It is assumed that the heavy naphtha stream boils in the range from about 250° F. to 425° F., and the gas oil stream boils in the range from about 400° F. to about 700° F. It is to be understood that distillation zone 20 may comprise any suitable number and arrangement of distillation units and that the number of streams segregated in said zone may vary with respect to boiling range and character. In accordance with my process, the heavy naphtha stream removed by means of line 24 is subjected to elevated temperature and pressure conditions in reforming zone 26 to produce relatively lower boiling hydrocarbon constituents which are removed by means of line 27 and a relatively high boiling tar fraction which is removed by means of line 28. Fixed gases and other boiling range streams are removed from zone 26 and handled in any desirable manner. The segregated fraction from zone 20 boiling in the gas oil boiling range and removed by means of line 25 is passed through

heating zone 29 wherein the same is vaporized. The vapors are then mixed with a powdered catalyst which is introduced by means of line 30 and the mixture introduced into catalytic cracking zone 31 wherein temperature and pressure conditions as well as the time of contact are adjusted to produce hydrocarbon constituents boiling in the motor fuel boiling range. The cracked vaporous product containing suspended catalysts is removed overhead from cracking zone 31 by means of line 32 and introduced into separation zone 33 wherein the catalyst is separated from the vapors and removed by means of line 34. The cracked vapors free of catalysts are removed from separation zone 33 by means of line 35 and passed into contacting zone 36 in which zone the vapors are treated preferably countercurrently with at least a portion of the tar fraction removed from reforming zone 26 by means of line 28. The tar fraction is introduced into the upper part of treating zone 36 by means of line 37. Temperature and pressure conditions are adjusted so that substantially no condensation of the vapors introduced into zone 36 by means of line 35 occurs. The treated vapors from which sulfur compounds have been separated are removed overhead from zone 36 by means of line 38 and further handled and refined as desired. The treating reagent comprising the tar is withdrawn from treating zone 36 by means of line 39 and handled as desired.

It is to be understood that modifications of the invention may be adapted. It may not be desirable to utilize the entire amount of the tar produced in reforming zone 26 in which case a portion of the same is withdrawn from the system by means of line 40. Under certain conditions it may be desirable to pass the crude bottoms removed by means of line 46 through thermal cracking zone 41 and to segregate a petroleum fraction boiling in the motor fuel boiling range by means of line 42 and also to segregate a tar fraction which is removed from zone 41 by means of line 43. Although it is preferred to utilize only the tar from reforming zone 26 in zone 36, under certain conditions it may be desirable to employ at least a portion of the tar from thermal cracking zone 41, in which case the tar is passed to zone 36 by means of line 44.

The process of my invention may be widely varied. It is to be understood that the process may be adapted in the treatment of cracked products produced in any catalytic cracking operation utilizing any feed stock or any catalyst. However, the process is particularly adapted for the treatment of products boiling in the motor fuel and heating oil boiling ranges derived from feed oils boiling in the gas oil and reduced crude boiling ranges, which products are secured by cracking said feed oils in the presence of a catalyst, as for example, a natural or acid treated clay, silica gel, synthetic clays, and the like. The heating oil fractions have gravities in the general range from about 22° A. P. I. to about 32° A. P. I., preferably gravities in the range from about 25° A. P. I. to 28° A. P. I. The heating oil fractions boil in the general range from about 300° F. to 650° F. In these catalytic cracking operations preferred catalysts comprise acid treated clay and synthetic clays. The operating conditions will vary considerably depending upon the particular feed oil being catalytically cracked and upon the particular catalyst employed. However, in general, the catalytic cracking operation is conducted at temperatures in the range from 76

700° F. to 1200° F., preferably at temperatures in the range from about 800° F. to 1000° F. and at pressures in the range from about atmospheric to about 50 pounds per square inch.

5 The cracked vapors produced by the above-described catalytic cracking operation are contacted with relatively high boiling hydrocarbon substances under conditions which are adapted so that substantially no condensation of the cracked vapors occurs. In general, I have found that it is preferred to contact the cracked vapors at a temperature in the range from about 600° F. to 850° F., preferably in the range from about 750° F. to 800° F.

10 15 The hydrocarbon substance preferably comprises a petroleum residuum, such as a petroleum tar. In general, it is preferred that the tar fraction have a gravity in the range from about -10° A. P. I. to +15° A. P. I. Although the tar fraction may have a sulfur content in the range from about 4% to 5%, it is preferred that the sulfur content of the same be in the range below about 1%, preferably in the range below about 0.5%. For this reason, a tar fraction segregated from a relatively low boiling oil, such as a heavy naphtha cut boiling in the general range from about 225° F. to 425° F., is particularly desirable. I have found that a highly cracked tar which has been produced in a cracking operation in which 20 25 30 35 relatively high temperatures are employed is desirable. This increases the desirability of utilizing a tar fraction segregated in the reforming of a heavy naphtha fraction, since heavy naphtha fractions are reformed at temperatures appreciably higher than those employed in the cracking of relatively higher boiling fractions, such as gas oil fractions and reduced crude fractions. The activity of the tar with respect to its ability for the removal of sulfur decreases with time. It is therefore desirable in the removal of sulfur compounds to employ a tar fraction which is 40 45 50 passed directly into the treating zone from the reforming zone.

In order to illustrate the invention further, the following examples are given which should not be construed as limiting the same in any manner whatsoever.

Example 1

A West Texas petroleum oil fraction boiling in the gas oil boiling range which had a sulfur concentration of 1.88% was cracked at a temperature of about 950° F. at a pressure of about 750 pounds per square inch. No catalyst was employed. The sulfur concentration in the respective segregated cracked fractions was as follows:

	Per cent sulfur
West Texas gas oil	1.88
Motor fuel—400° F. end point	0.5
Heating oil	1.2
Gravity, °A. P. I.	32.1°
Initial boiling point	218° F.
10% distilled at	415° F.
50% distilled at	480° F.
90% distilled at	568° F.
Final boiling point	618° F.
Heavy cycle gas oil	2.0
Tar (10° A. P. I.)	2.5

Example 2

In another operation, a West Texas reduced crude having a sulfur concentration of 3.12% was cracked at a temperature of 910° F. and at a pressure of 750 pounds per square inch. The

sulfur concentration in the respective cracked fractions was as follows:

	Per cent sulfur
West Texas gas oil	3.12
Motor fuel—400° F. end point	0.8
Heating oil	1.5
Gravity, °A. P. I.	32.5°
Initial boiling point	214° F.
10% distilled at	408° F.
50% distilled at	474° F.
90% distilled at	575° F.
Final boiling point	622° F.
Heavy cycle gas oil	2.7
Tar (10° A. P. I.)	3.5

From the above, it is apparent that the sulfur concentration of the heating oil is appreciably less than the sulfur concentration of the feed oil.

Example 3

A West Texas gas oil, similar to that utilized in the operation described in Example 1, was catalytically cracked at a temperature of 850° F. The sulfur concentration in the segregated cracked product was as follows:

	Per cent sulfur
West Texas gas oil	1.88
Motor fuel—400° F. end point	.165
Heating oil	1.87
Gravity, °A. P. I.	23.5°
Initial boiling point	242° F.
10% distilled at	438° F.
50% distilled at	460° F.
90% distilled at	540° F.
Final boiling point	627° F.
Heavy cycle gas oil	2.12

From the above it is apparent that in a catalytic cracking operation the sulfur concentration in the heating oil is practically identical with the sulfur concentration in the feed oil to the cracking zone.

Example 4

In an operation conducted identical to that described with respect to Example 3, except that the cracked products were contacted with a tar segregated from a heavy naphtha reforming operation, the results are as follows:

	Per cent sulfur
West Texas gas oil	1.88
Motor fuel—400° F. end point	.153
Heating oil	.95
Gravity, °A. P. I.	23.5°
Initial boiling point	242° F.
10% distilled at	438° F.
50% distilled at	460° F.
90% distilled at	540° F.
Final boiling point	627° F.
Heavy cycle gas oil	1.60

Thus, it is apparent that the process of the present invention materially aids in the removal of sulfur from heating oil fractions.

What I claim as new and wish to protect by Letters Patent is:

- 5 1. Process for removal of sulfur compounds from hydrocarbon vapors produced in catalytic cracking operations which comprises contacting said hydrocarbon vapors with a relatively high boiling liquid hydrocarbon having a gravity in the range from about —5° A. P. I. to about +10° A. P. I. at a temperature in the range from about 600° F. to 850° F.
- 15 2. Process for the production of a relatively low sulfur heating oil fraction, which comprises catalytically cracking a feed oil, separating hydrocarbon vapors comprising constituents boiling in the heating oil boiling range, contacting the hydrocarbon vapors with a petroleum oil tar under conditions so that substantially no condensation of the hydrocarbon vapors occurs, separating the hydrocarbon vapors and segregating the heating oil therefrom.
- 20 3. Process as defined by claim 2, in which said tar comprises a cracked tar and is characterized by having a gravity in the range from about —5° A. P. I. to about +10° A. P. I.
- 25 4. Process as defined in claim 2, in which said feed oil comprises a petroleum oil fraction boiling in the gas oil boiling range and in which said petroleum oil tar is segregated from a heavy naphtha reforming operation.
- 30 5. Process for the segregation of a cracked low sulfur heating oil fraction from a petroleum crude oil, which comprises segregating a petroleum crude oil into fractions comprising a heavy naphtha fraction and into a gas oil fraction, reforming said heavy naphtha fraction and segregating tar therefrom, catalytically cracking said gas oil fraction under conditions to produce vapors comprising heating oil constituents, countercurrently contacting said vapors with said tar, separating the vapors and recovering a low sulfur heating oil therefrom.
- 35 45 6. Process as defined by claim 5, in which said heavy naphtha fraction boils in the range from about 250° F. to 425° F., and in which said gas oil fraction boils in the range from about 400° F. to 700° F.
- 50 55 7. Process as defined by claim 5, in which said heavy naphtha fraction boils in the range from about 250° F. to 425° F., said gas oil fraction boils in the range from about 400° F. to 700° F., and in which said tar has a gravity in the range from about —5° A. P. I. to about +10° A. P. I.

HAROLD J. MOYER.
